L. S. KALLAJIAN,
TELEPHONE RECEIVER HOLDER,
APPLICATION FILED DEC. 13, 1916.

1,319,774.

Patented Oct. 28, 1919.

Inventor,
Lazarus S. Kallajian;
By *St. B. Lopham*,
Attorney.

UNITED STATES PATENT OFFICE.

LAZARUS S. KALLAJIAN, OF BOSTON, MASSACHUSETTS.

TELEPHONE-RECEIVER HOLDER.

1,319,774.

Specification of Letters Patent. Patented Oct. 28, 1919.

Application filed December 13, 1916. Serial No. 136,787.

To all whom it may concern:

Be it known that I, LAZARUS S. KALLAJIAN, a citizen of the United States, and a resident of Boston, in the county of Suffolk and Commonwealth of Massachusetts, have invented certain new and useful Improvements in Telephone-Receiver Holders, of which the following is a full, clear, and exact specification.

10 The object of this invention is the construction of a holder for telephone receivers which shall embody the improvements hereinafter set forth.

In the drawings forming part of this specification, Figure 1 is a perspective view of the entire device, showing the receiver supported thereby. Fig. 2 is an elevation of a portion thereof, parts being in section, showing the telephone transmitter connected therewith. Fig. 3 is a detail view of the pivotal portion of the receiver-holder arm. Fig. 4 is a horizontal section of a telephone standard illustrating said pivotal portion clamped to the standard. Fig. 5 is a detail view of the receiver hand.

One of the purposes of the invention being the construction of a receiver holder which could be instantly removed from its connection with the telephone, without the manipulation of any screw or other fastening device, I have supported the holder by an instrumentality adapted to receive the transmitter and to be held in engagement therewith by the weight of the latter.

35 To this end, I provide a base 1 illustrated in Fig. 1 as rectangular in outline, having a seat 2 therein disposed to receive the base 3 of the transmitter standard 4. From the base 1 extend two arms 5 upward 40 and inward to the lower end of an upright 6 which is concaved to fit the exterior of the standard 4, and whose outer surface is correspondingly rounded. The transmitter support having had its base 3 inserted within the seat 2, its standard 4 is in snug contact with the upright 6, as indicated in Fig. 2.

To the upper end of the upright 6 is pivoted a curved arm 7 having a socket 9 in its free end slidably receiving a slender rod 10 held in place therein by a thumb screw 11; the upper end of the rod having a clasping device preferably in the shape of a human hand 12, into which the receiver 13 is slipped and securely held from falling out, as illustrated in Fig. 1.

The arm and rod are designed to be limited to a swing of somewhat less than ninety degrees, between the position shown in Fig. 2 and another about equally behind a vertical plane cutting its pivotal point. For thus limiting its play, the pivotal end of the arm 7 is formed with two stops 14 co-acting with the shoulder 15 formed on the upright 6.

From the arm 7 projects a stud or screw 16 adapted by its descent as the arm 7 is swung rearward, to depress the circuit closing hook 17 and hold the telephone inoperative. When it is desired to use the phone, the arm 7 is swung forward to the position shown in Fig. 2, the stud or finger 16 releases the hook, and the circuit is closed.

Normally, of course, the receiver 13 is supported in the rearward position and the circuit broken, but when the phone is to be used, the receiver and arm are pulled forward, thereby permitting the closure of the circuit, and when the user's mouth is presented to the transmitter, the receiver should be close to his ear, the slideable and rotary adjustments of the rod 10 permitting the same to be fitted to any individual. Usually, however, when adjusted to one adult it will fit sufficiently close any other adult.

By unloosening the thumb screw 11, the receiver can be adjusted both vertically and rotatively to properly present itself to the user's ear when his mouth is close to the transmitter. Consequently the telephone can stand upon the user's desk or table near at hand so that he can talk and hear and at the same time use both hands for taking notes, referring to books and letters, and the like.

It will be seen that the auxiliary base 1 not only serves as a means for keeping the standard in place therein, but provides an extension which acts to keep the weight of the receiver from overbalancing the telephone. This function is obtained by having one of the corners of the base 1 extending outward toward a point directly below the supported receiver.

While the seating of the telephone base 3 within the auxiliary base 1 confines the receiver supporting means securely to the transmitter standard, the latter can be removed therefrom at will and without unfastening any screws or other attaching devices. Likewise, the receiver is equally se-

cure in the hand or seat 12 in all of its positions and conditions of use, while being similarly removable therefrom. This is due to the tapering form of the usual receiver, and 5 to the corresponding formation of the hand. Further, the latter is constructed with its imitation fingers and thumb inclosing more than half of the periphery of the receiver-circle, as shown in Fig. 5, so that the space 10 between the end of the thumb and the finger-tips is but slightly more than the diameter of the smaller end of the receiver. Hence, by introducing the smaller section of the receiver down between the thumb and fingers 15 and then sliding it along until its larger diameter snugly fits the larger portion of the hand-opening, the receiver is securely held in place. The inclination downward given to the smaller end of the receiver by the 20 hand, as shown in Fig. 1, maintains the described security of position.

As indicated in Fig. 4, the pivotal support for the arm 7 and hand 12 may be clamped directly to the standard 4, and the 25 auxiliary base and upright 6 dispensed with, but the arrangement first described is much to be preferred, both for the readiness of the separation of the telephone therefrom, and for the base-extension and avoidance of over- 30 balancing by the receiver. The upright is made thin and rounded both externally and interiorly to render it less conspicuous and more attractive in appearance, to give increased strength with minimum weight of 35 metal, and also to enable the entire structure to be held in the hand if desired, the hand clasping the standard and upright as freely as it can the standard alone.

As shown in Fig. 1, the arm 7 is formed 40 with two screw-holes 18 for enabling the stud 16 to be shifted thereon so as to accommo-

date telephones which have circuit-closing hooks 17 differing in heights.

What I claim is:

1. The combination with a telephone 45 standard having a base, of a support comprising an auxiliary base removably receiving the telephone base, a semi-cylindrical shell rigidly supported by the auxiliary base to fit against the telephone standard when 50 the telephone base is located in the auxiliary base and to be instantly removed therefrom, and means connected with the upper part of said shell for supporting a telephone receiver. 55

2. The combination with a telephone having a standard and a base, of a support comprising an auxiliary base having a depressed seat therein for said base, the margin of the auxiliary base being extended at two points, 60 a vertical member or upright having a concave surface fitting a portion of the said standard, two legs joining the lower part of said upright to said extended points, and a carrier-arm for the telephone receiver connected with the upper part of the upright. 65

3. The combination with a telephone standard having a circular base, of a support comprising a rectangular base having a circular flanged seat therein to receive the 70 standard base, an upright having one face concave to fit said standard and the other face convex substantially concentric therewith, two curved legs rising from two adjacent corners of the rectangular base and 75 supporting said upright, and an arm pivotally supported at the upper end of said upright for carrying the telephone receiver.

In testimony that I claim the foregoing invention, I have hereunto set my hand this 80 10th day of December, 1916.

LAZARUS S. KALLAJIAN.
